MESSAGE HOLDER FOR TELEPHONES

Filed Aug. 8, 1931

UNITED STATES PATENT OFFICE

ROBERT H. BARCLAY, OF NEW YORK, N. Y.

MESSAGE HOLDER FOR TELEPHONES

Application filed August 8, 1931. Serial No. 555,958.

My invention relates to message holding means for attachment on telephones, and the same has for its object to provide a simple, efficient and convenient device which may be 5 readily interengaged with the telephone in position for use without interfering with the operation of the telephone.

Another object of the invention is to provide a device of the character specified which 10 is particularly adapted for use with telephones of the French type.

Another object of the invention is to provide a device of the character specified in which the means for attaching the device is in 15 its entirety formed integrally with a portion of the message holding means thereof.

Another object of the invention is to provide a device of the character specified in which the attaching means thereof is adapted 20 to be interengaged with and locked in position on a telephone prong by a simple movement without the use of screws or other auxiliary fastening means to secure the same in place.

25 Other objects will in part be obvious and in part be pointed out hereinafter.

In the accompanying drawing:

Figure 1 is an elevation of one form of device constructed according to and embodying 30 my said invention, the same being shown attached to the telephone;

Fig. 2 is a side elevation thereof; and

Fig. 3 is a perspective.

Referring to the drawing, the French telephone 35 10 includes the prongs 12 for receiving therebetween the combined transmitter and receiver 14. The member 14 when disposed between the prongs holds the actuating means 16 depressed to open the circuit.

40 The message holder 17 comprises a strip of thin material, preferably metal, having an apertured lower portion 18, constituting attaching means. The aperture or opening 20 conforms in shape and size to the cross-section 45 of the telephone substantially at the base of the prong 12, as indicated at Fig. 1. The upper portion 22 of the strip 17 is arranged angularly relative to the lower portion, as indicated at Fig. 2 and yieldable fingers or 50 detents 24 are formed at the juncture of the

two portions and are adapted to engage and lock around the opposite sides of the prong 12. A spring tongue or clip 26 is secured at one end to the upper side of the portion 22 and cooperates therewith for receiving messages or 55 papers therebetween.

The device 17 is adapted to be interlocked with one of the prongs 12, preferably a prong at the rear of the telephone. In attaching the device the member 14 is temporarily removed. The device 17 is held with the tongues 24 facing upwardly, and the apertured portion 18 placed about the prong. When the device reaches its lowermost position it is then tilted towards the rear to bring the tongues 24 into engagement with the opposite sides of the prong, the lower portion 18^a engaging below the prong substantially as shown at Figs. 1 and 2. The device is thus securely locked against vertical movement in both directions by the portion 18, and the engagement of the device with the inner side of the prong prevents rearward movement, the spring tongues 24 holding the device against movement in the opposite direction away 70 from the prong. 75

The device when in position closely hugs the inner side of the prong, while the portion 22 extends outwardly over the prong. The member 14 can thus be readily removed and replaced without being interfered with by the device. Any message A may be readily inserted below the clip 26 where it can be 80 readily seen.

85 My device is simple in construction, and may be readily placed in position without the use of separate fastening devices, such as bands or screws, the attaching means 18 in its entirety being formed integrally with the device, and the device, being composed of thin strip-like material, takes up very little space between the prongs.

Having thus described my invention, what I claim and desire to secure by Letters Patent is:

1. A device of the character described comprising a member having an apertured lower portion adapted to engage about a telephone prong at the base thereof and extend along 100

the inner side thereof, said lower portion including a transverse part below the aperture adapted to extend under the prongs means on the member for retaining the device in engagement with the inner side of the prong, and means on the upper portion of the member for holding messages.

5 2. A device of the character described comprising a member having an integrally formed apertured portion and tongues, said apertured portion being adapted to engage about a telephone prong at the base thereof and including a part below the aperture adapted to extend under the prong, and said 10 tongues locking the member to the prong, and message holding means on the member.

15 3. A device of the character described comprising a strip having an apertured lower portion including a part below the aperture and spring fingers above said apertured portion, said apertured portion being adapted to engage about a telephone prong at the base thereof with said part extending under the base of the prong and to extend along 20 the inner side of the prong to be locked there-to by said fingers, and message holding means on the upper portion of the strip.

25 4. A device of the character described comprising a member having an apertured lower portion adapted to engage about a telephone prong at the base thereof and including a part extending under said base, the upper portion of said member being arranged at an 30 angle to the lower portion to extend outwardly over said prong, and message holding means carried by said upper portion.

35 5. A device of the character described comprising a strip having an aperture at the lower portion thereof adapted to fit a telephone prong at the base thereof and to extend 40 along the inner side thereof, spring fingers formed integrally with said strip above the aperture and adapted to engage the prong to 45 hold the device in position, the upper portion of the strip extending outwardly at an angle to the lower portion in the direction of projection of said fingers, and message holding means on the upper portion.

50 6. A device of the character described comprising a member having complete means formed integrally therewith for attaching the same to the prong of a telephone, said 55 means including a portion receiving the prong at the base thereof and extending transversely under the base, and means for retaining the member in engagement with the inner side of the prong, and means on the 60 member for holding messages.

65 7. A device of the character described comprising a strip having a lower portion for engagement about a prong at the base thereof and including a part extending under the 70 prong to prevent vertical movement of the

device relative to the prong when secured in position, means for retaining said strip in engagement with the inner side of the prong, and message holding means on the upper portion of the strip.

75 8. A device of the character described comprising a strip having a lower portion for engagement under a prong at the base thereof to prevent vertical movement of the device when secured in position, fingers for retaining said strip in engagement with the inner side of the prong, the upper portion of said strip extending outwardly at an angle in the direction of projection of said fingers, and message holding means on the upper portion 80 of the strip.

85 In testimony whereof, I have signed my name hereto.

ROBERT H. BARCLAY.
